G. H. GILMAN

DRILLING MACHINE

Filed April 30, 1920

Inventor:
George H. Gilman,
by Emery, Booth, Jamley & Farmer,
Atty's.

UNITED STATES PATENT OFFICE.

GEORGE H. GILMAN, OF BOSTON, MASSACHUSETTS.

DRILLING MACHINE.

Application filed April 30, 1920. Serial No. 377,763.

The invention relates to drilling machines and more particularly but not exclusively to hammer rock drills.

The invention will be best understood from the following description when read in connection with the accompanying drawings, of an example of the invention, while the scope of the invention will be more particularly pointed out in the appended claims.

10 In the drawings:

Fig. 1 is a longitudinal section through a hammer rock drill;

Fig. 2 is a section on the line 2—2 of Fig. 1;

15 Fig. 3 is a section on the line 3—3 of Fig. 1;

Fig. 4 is a section on the line 4—4 of Fig. 1;

20 Fig. 5 is a fragmentary section corresponding to Fig. 1 showing the valve at the opposite end of its travel; and

Fig. 6 is a section on the line 6—6 of Fig. 3 with the valve omitted.

Referring particularly to Figs. 1 to 4, 25 the embodiment of my invention which I have selected for purposes of illustration includes a casing comprising a cylinder member 1, a front head structure 2 and rear head structure 3. Mounted for reciprocation in the cylinder is a piston 4 provided with a hammer bar 4^a while rotatably mounted in the front head structure is a chuck 5 provided with a polygonal recess for receiving the polygonal end 6 of the drill 30 steel 7. The drill steel is arranged in the present construction to be impacted by the hammer bar, the latter extending from the cylinder into the front head structure and being surrounded by the rearwardly extending portion 8 of the chuck.

As shown in the rear head structure 4 is mounted a ratchet disk 10 provided with a bar 11 extending through the cylinder and into the recess 9 of the piston, the teeth 45 of the ratchet disk cooperating with suitable spring pressed pawls 12 to permit rotation of the bar in the direction indicated by the arrow in Fig. 1 and to prevent rotation in the opposite direction. Cooperating with the hammer bar in a manner hereinafter to be described I have shown a ratchet ring 13 mounted in the front head structure and surrounding the hammer bar, the ring being provided with a rearward-

ly extending portion 14 which provides an 55 exterior bearing for the ring in the front cylinder head 15 as is clearly illustrated by Fig. 1. On the exterior surface of the ring 13 I provide ratchet teeth which cooperate with the spring pressed pawls 20 to prevent 60 rotation of the ring in the direction opposite to that indicated by the arrows around the rifle bar and the drill steel.

For connecting the piston to the bar 11 and for connecting the hammer bar to the chuck 65 and the ring I have herein provided slots or grooves and cooperating followers. The grooves of the connection between the bar 11 and the piston are preferably formed on the exterior surface of the bar and the followers on the interior surface of the nut 16 carried by the piston. The grooves of the connections between both the ring and chuck with the hammer bar are preferably formed on the exterior surface of the latter and 70 the followers on the interior surface of the former. The grooves for connecting the piston to the bar 11 and those connecting the hammer bar to the chuck are preferably 75 in the form of helical grooves 17 and 18 oblique to the axis of the piston and hammer bar while the grooves connecting the hammer bar to the ring are preferably in the form of straight grooves 19 for forming a feather connection. Respectively cooperating with the grooves 17, 18 and 19 are the lugs 21, 23 and 22. For the reason herein-after pointed out, the grooves 18 are preferably of one-half the pitch of the grooves on the bar 11 and both sets of grooves are 80 pitched in the same direction. The bar 11 is 85 will hereinafter be referred to as the rifle bar.

The operation of the mechanism so far described is as follows: When motive fluid 95 is admitted to drive the piston from the position shown in Fig. 1 to the rear end of the cylinder, the piston, owing to the action of the cam surfaces afforded by grooves 18 and their followers, tends to rotate in the direction opposite to that indicated by the arrows in Fig. 1. This rotation is prevented by the pawls cooperating with the ring and consequently the piston moves backwards without rotation and this through 100 the action of the grooves 18 and their followers rotates the chuck and rifle bar in the direction indicated by the arrows. When 105

motive fluid is admitted to drive the piston from the rear to the forward end of the cylinder, the piston tends to rotate the rifle bar in the direction opposite to that indicated by the arrows in Fig. 1. This rotation is prevented by the pawls cooperating with the teeth on the ratchet 10 and consequently as the piston advances, it is rotated by the action of the followers 21 on the cam surfaces afforded by the grooves 17 in the direction of the arrows and therefore it rotates the chuck through the action of the grooves 18 and cooperating followers 23. During the forward stroke the ring 13 rotates with the piston. It will be noted that a forward reciprocation of the piston tends to rotate the chuck relatively thereto by action of the grooves 18 in the opposite direction to which the piston is then rotating and therefore, the absolute rotation of the chuck is dependent upon the difference in pitch between these grooves and the grooves 17 on the rifle bar. Consequently if the pitch of the grooves 18 is one-half that of the grooves 17, the chuck is rotated at one-half the speed of rotation of the piston or in other words, it is rotated at the same speed or through the same angle on the forward stroke of the piston as it is rotated on the rearward stroke of the piston.

For controlling the active fluid for reciprocating the piston I have shown a suitable valve 24 mounted in the casing 25 formed integrally with the cylinder portion 35 and extending longitudinally of the cylinder at one side thereof. This casing I preferably construct to form a reduced diameter portion 26 and an enlarged diameter portion 27. In the enlarged diameter portion are provided the annular grooves 28 and 29 while in the reduced diameter portion are provided the annular grooves 30 and 31. The grooves 28, 29, 30 and 31 respectively communicate with the cylinder by means of passages 32, 33, 34, 35.

Mounted for reciprocation within the valve casing is a valve 24 provided with the heads 36 and 37 of diameters corresponding to those of the enlarged and reduced portions 50 of the valve casing. Intermediate the heads 36 and 37 the valve is provided with the reduced portion 38. This valve is tubular in form, being provided with the internal conduit 39.

At the end of the enlarged head 36 of the valve is formed a poppet seat 40 cooperating with the corresponding valve seat 41 formed on the bushing 42, this bushing being provided with a passage 43 communicating with the motive fluid supply 44.

Communicating with the valve casing intermediate the heads 36 and 37 are conduits 45 and 46 and formed in the interior wall of the cylinder is a longitudinally extending groove 47 with which the passage 34 com-

municates. Preferably, I form one portion of the head 36 adjacent the poppet seat with a bevel 48 and provide the forward end of the bore of the valve with a similar bevel 49. These bevels, although they are not absolutely necessary for the successful operation of my valve are provided to improve its efficiency.

The operation of the valve is as follows: Assume the valve is in the position illustrated by Fig. 1. Under these conditions, the motive fluid passes through the bore 39 of the valve and flows around the rear end thereof and enters the forward end of the cylinder through the groove 31 and passage 35. The piston now moves rearwardly, the motive fluid in front of the piston exhausting through the passage 33 and annular groove 29 into the space about the reduced portion 38 of the valve whence it discharges to the atmosphere through the passages 45 and 46. After the piston moves rearwardly far enough to cover the port 33 the motive fluid in front of the piston is trapped and compressed to a high enough pressure to overcome the pressure of the motive fluid on the forward end of the valve, this compressed fluid acting on the poppet face and its bevel 48 to throw the valve forwardly.

When the valve moves forwardly, the pressure acting on the poppet face 40 holds the valve in its forward position as illustrated by Fig. 5 and the motive fluid now flows across the seat and enters the cylinder through the passage 32 and forces the piston forwardly, the motive fluid now exhausting through the groove 47, passage 34, annular space around the reduced portion of the valve and passages 45 and 46 to the atmosphere. In its forward stroke, after the rear end of the piston uncovers the groove 47, the motive fluid behind the piston discharges to the exhaust and reduces the pressure of the air on the poppet seat of the valve. This reduction of pressure permits the live air acting on the forward end face of the valve and its bevel 49 to throw the valve rearwardly. It will be appreciated that the opening of the groove 47 to the high pressure air behind the piston builds up a considerable pressure in the exhaust chamber formed by the reduced portion 38 of the valve and this pressure acting on the unbalanced area of the head 36 aids the live air acting on the forward end of the valve to move it. The position of the parts are now as shown by Fig 1 and the operation is repeated.

The groove 47 is made of such dimensions as to permit a prolonged exhaust on the forward stroke of the piston and the exhaust of air from behind the piston on this stroke at the proper time to throw the valve rearwardly. It will be noted that the groove 47 when uncovered by the piston connects the admission passage 32 with the exhaust pas-

sage 34 by way of the cylinder and therefore acts to place the opposite sides of the head 36 of the valve in fluid communication.

Although I have described one specific embodiment of my invention it is to be understood that my invention is not limited thereto and that extensive deviations may be made without departing from the spirit of my invention.

10 Claims:

1. In a hammer rock drill, a casing, a chuck rotatably mounted in said casing, a hammer piston in said casing having a hammer bar, a rifle bar having a helical groove and lug connection with said piston and ratchet connection with said casing, a ring surrounding said hammer bar and having a ratchet connection with said casing; lug and groove connections between said hammer bar and ring and hammer bar and chuck, one of which grooves is helical and the other parallel to the axis of said chuck; and the direction of rotation of said rifle bar and ring permitted by the respective ratchets and the pitch of said helical grooves being such as to enforce rotation of said chuck for each direction of reciprocation of said piston.

2. In a hammer drill, a hammer piston, a drill steel, means for rotating said piston on one of its strokes, means for preventing rotation of the piston on the next successive stroke, and a connection between said piston and drill steel so formed that on each of said strokes the steel is rotated in the same direction.

3. In a hammer drill, a hammer piston, a drill steel, a chuck carrying said drill steel means for rotating said piston on one of its strokes, means for preventing rotation of the piston on the next successive stroke, and a connection between said piston and chuck so formed that on each of said strokes the chuck is rotated in the same direction and at the same speed.

4. In a hammer drill, a piston, a chuck, means for holding the piston from rotating on one stroke, a connection between the piston and chuck for causing the rectilinear motion of the piston to rotate the chuck when so held, and means for rotating the piston on the opposite stroke whereby the piston through said connection rotates the chuck in the same direction.

5. In a hammer drill, a piston, a chuck, means for holding the piston from rotating on one stroke, a connection between the piston and chuck for causing the piston to rotate the chuck when so held, and means for rotating the piston on the opposite stroke at twice the speed that the chuck was rotated on the first mentioned stroke whereby the piston through said connection rotates the chuck in the same direction as before and at the same speed.

6. In a rock drill, a casing, a hammer

piston therein having a hammer bar, a chuck, a helical lug and groove connection between said hammer bar and chuck, means for causing the piston to travel with a predetermined angular movement relative to said casing on the rear stroke whereby said chuck is rotated, and means for rotating said piston on the opposite stroke whereby said chuck is again rotated in the same direction.

7. In a rock drill, a casing, a hammer piston therein having a hammer bar, a chuck, a helical lug and groove connection between said hammer bar and chuck, means for causing the piston to travel with a predetermined angular movement relative to said casing on the rear stroke whereby said chuck is rotated, and means for rotating said piston on the opposite stroke whereby said chuck is again rotated in the same direction, and at the same speed.

8. In a rock drill, a casing, a hammer piston therein having a hammer bar, a chuck, a helical lug and groove connection between said hammer bar and chuck, means for causing the piston to travel with a predetermined angular movement relative to said casing on the rear stroke whereby said chuck is rotated, and a rifle bar operative to rotate said piston on the opposite stroke whereby said chuck is again rotated in the same direction.

9. In a rock drill, a casing, a hammer piston therein having a hammer bar, a chuck, a helical lug and groove connection between said hammer bar and chuck, means for causing the piston to travel with a predetermined angular movement relative to said casing on the rear stroke whereby said chuck is rotated, and means for rotating said piston on the opposite stroke in the same direction and at twice the speed of such chuck rotation whereby the chuck is again rotated in the same direction and at the same speed.

10. In a hammer drill, a casing having therein a rotatable chuck and a hammer piston, a helical cam connection between said piston and chuck, means including a pair of ratchet devices having a slip connection with said piston for causing said piston to rotate on one stroke in the same direction as that in which said chuck rotates and be withheld from rotation on the other stroke, and said ratchet devices being rotatable in only one and the same direction, whereby said piston when withheld from rotation rotates said chuck in one direction and when rotated rotates said chuck in the same direction.

11. In a hammer drill, a casing having therein a rotatable chuck and a hammer piston, a helical cam connection between said piston and chuck, a pair of ratchet devices rotatable in only one and the same direction, a slip connection between one of said ratchet devices and said piston comprising a helical

cam connection of twice the pitch as the first named helical cam connection for rotating said piston on one stroke, whereby said piston rotates said chuck in the same direction as said piston at one-half the speed of rotation of said piston, and a slip connection between the other of said ratchet devices and said piston for preventing said

piston from rotating on the opposite stroke for causing said piston to rotate said chuck ¹⁰ at the same speed and in the same direction as on the first mentioned stroke.

In testimony whereof, I have signed my name to this specification.

GEORGE H. GILMAN.
